GEORGE E. BARNHART, OF PASADENA, CALIFORNIA.

HEAT-TREATING-FURNACE ORGANIZATION FOR METALLIC UNITS.

Application filed November 26, 1926. Serial No. 150,754.

Although my invention is entitled somewhat broadly as pertinent to heat-treating means and methods, this invention relates more particularly to a simple and highly efficient furnace suitable for use in the heating of rods or tubes; a combination including such a furnace and a quench tank therebelow; and to methods wherein said furnace and said tank and auxiliary devices may be advantageously employed.

Although my present invention is capable of use in the heat treatment of a great variety of metallic units, it is a particular object of my invention to provide means and methods suitable to use in the heat treatment of tapered or other tubular elements,—such as may be employed in the construction of golf sticks, masts or other structural elements having a considerable length in proportion to the diameter thereof; and my invention is herein accordingly described with reference more particularly to the heat treatment of such tubular elements.

Other objects of my invention (including means and methods of producing a substantially uniform and/or controlled high temperature within a substantially cylindrical furnace; means and methods favorable to the establishment of uniform or varying temperatures in such furnaces; means and methods for predetermining the rate of descent of treated units into and through quench tanks; means and methods for locally varying the effect of a quench liquid upon the treated units) may be best appreciated from the following description of an illustrated embodiment of my invention, taken in connection with the appended claims and the accompanying drawings, in which

Fig. 1 may be referred to as, for the most part, a vertical section through an installation or apparatus embodying my invention,—various parts being shown in elevation and/or broken away.

Fig. 2 may be regarded as a separate top plan view of a furnace shown in the upper portion of Fig. 1.

Fig. 3 is a horizontal section taken substantially as indicated by the lines 3—3 of Fig. 1.

Fig. 4 is an elevational view, showing, in vertical section, a guard hereinafter referred to as suitable for use in protecting a portion of a unit, such as a golf-stick shaft, from any undesired or excessive chilling effect,

during the descent thereof through a quench tank.

Fig. 5 is a view, comparable to Fig. 4, but showing a larger unit as provided with a series of removable and perforated conical elements, adapted individually or collectively to regard the descent of a unit and to influence the rate of cooling thereof,—an uppermost conical element being shown as imperforate, for a purpose hereinafter mentioned.

Referring to the details of that specific embodiment of my invention chosen for purposes of illustration, I show at 11 a substantially cylindrical furnace which is provided, near the bottom thereof, with a lateral opening 12 for the projection tangentially inward of a frame 13,—said furnace being provided also with means for the support, for a heating effect, of a plurality of golf-stick shafts or other treated units 14.

The furnace 11 is shown as supported by a scaffold 15, including channel members 16 and a platform 17, above a quench tank 18; and the flame 13 is shown as projected by means comprising a burner 19, to which oil or gas may be admitted from a source of supply, such as a tank 20, by means of a valved pipe 21,—air or steam being delivered to said burner and to said flame respectively, by means such as separate valved pipes 22 and 23. The latter is shown as terminating in a separate nozzle 24, and air may be supplied thereto by means such as a pump or compressor 25, operated by a steam, electrical, or other motor 26.

Referring now to the more important and strictly novel features of the furnace 11, the platform 17 being preferably formed of a refractory material adapted to serve not only as a support for said furnace but to provide a bottom plate or end therefore, I show the said furnace as comprising a banded cylindrical jacket 27, surrounding a cylindrical body formed of specially shaped fire bricks 28,—outwardly and inwardly terminating in curved surfaces; and I show the upper end of said furnace as provided not only with a tangential outlet 29, leading to a stack or flue 30 but also with a built-up top or cover 31. The latter may advantageously comprise two layers of rectangular or other fire bricks 32, having a metallic plate 33 interposed therebetween; and said top and/or the plate 33 may be

provided with any desired number of apertures, in a central part thereof, to permit the insertion and support of the units 14 and/or a pyrometer 34, or its equivalent.

- 5 The illustrated pyrometer being of a thermal-couple type, temperature readings may be taken on a near or remote scale such as is indicated at 35; and a desired rate of spiral circulation of the flame 13, to cause 10 the same to follow a path such as that indicated by the arrow-line 36, and to effect a comparatively uniform heating of all parts of all the units 14, may be aided not only by means such as a deflecting plate 37, preferably positioned opposite or near the inlet 12 but by damper means such as a horizontally slideable plate 38. The latter may be merely a loose brick, of rectangular or other suitable shape, movable by means such as a 15 handle 39.

The plate 33, or a suitable part separable therefrom is provided with an aperture or plurality of apertures generally indicated by reference numeral 40 through which the respective units 14 may be supported by means such as wires 41 which are diagrammatically illustrated as being removably secured to posts or pins 42. It is considered preferable to interpose a muffle 43 between the 20 top plate 33 and the bottom platform 17, such a construction being favorable to a uniformity of heating effects and to an avoidance of oxidation. As an aid to initially heating the chamber enclosed by the 25 muffle 43 and to maintain a uniform temperature therein with a minimum loss of heat, the central bottom opening 44, formed below the muffle 43 is illustrated as being provided with a closure element or door 45.

- 30 40 The bottom closure element on door 45 is shown as pivoted at 46 and as provided with an operating arm 47; in case the arm 47 is of such form and weight as to overbalance said closure element, tended normally to hold the same closed, a withdrawal 35 thereof may be effected by means such as a chain or cord 48, shown as extending over a pulley 49 and as terminating in a loop 49', adapted to be held by a fixed hook 50.

- 45 50 Although the closure 45 may be opened at any time, in order to vary the temperature within the muffle 43 or within a circular or annular exterior or flame chamber 51, in the event a muffle 43 is not used, it 55 will be understood that the opening of this closure is, in any event, intended to precede the dropping of the units 14, (as by unhooking or clipping the wires 41 or by batch-release means such as are hereinafter 60 mentioned) into the quench tank 18, or its equivalent.

In order to permit the heated units to acquire any desired velocity of descent before entering a body 52 of water, oil or any preferred chemical confined within said tank, 65

the latter may be elevated or depressed to any desired level,—as by the adjustment of a jack or jacks 53; and/or the rate of descent of the units after they have been heated to a desired extent, may be varied by 70 securing thereon, in advance of the described heating, any desired number of conical or other retarding elements of the general character shown at 54,—these being optionally perforated and adapted not only to obviate the necessity for using a very deep quench tank 18, by retarding the descent of the unit 14' therethrough, but also to assure a maximum heat exchange and consequent cooling effect, during the descent of the units 75 through the quench liquid 52. By the use of the cones 54, I may reduce the height of a quench tank to about one-fourth of that otherwise required.

Together with or independently of the retarding cones 54, or their equivalent, in case a local annealing effect is desired, in order to avoid an unduly sudden or rapid chilling of certain parts of the units 14 or 14', I may apply, to a part or parts in which a toughening effect is desired, a guard or guards of the general character best illustrated at 55 in Figs. 1 and 4. Each of these guards preferably comprises an upwardly or a downwardly diminishing body 56 and a horizontal plate 57, said body and said plate being respectively provided with openings, as at 58 and at 59, suitably proportioned to fit closely upon the units 14 (or 14') and to render the same self-retaining in a desired 100 position upon said units.

By means of the general character just described, I may so quench a batch of the described units as to assure a suitable stiffness and resiliency therein, incidentally 105 effecting a toughening of a portion or portions of said units, as for the purpose of adapting the same to be drilled (in the case of golf-stick shafts) for the attachment of heads of any desired character thereto.

It will be understood that the size of the retarding members 54 and/or the excluding members 55 may depend not only upon the rate of descent and the effects desired but also upon the weight and character of the units 14, 14',—cones varying between 2 inches and 20 inches in diameter being suitable to use in the connection referred to, within a tank having a diameter of 24 inches, more or less, subsequently to the heating of the described units to temperatures of about 1600° to 1800° F., for periods such as 16 seconds; but it should be clearly understood that my described furnace may be used not only for the indicated heat-treating and/or annealing effects but also, if desired, for carbonizing effects,—as by the introduction of a carbonizing gas, such as ordinary illuminating gas or other suitable gas, through an additional pipe 60, or its equivalent; that 120 125 130

the muffle 43 may be either included or omitted,—the described construction being such that the flame 13 is, in any event, disposed to hug the outer wall 61 of the chamber or passage 51; and that the action of the described flame (where produced by the use of one or more jets, consuming either gas or oil—oil being preferred and said jets being disposed either at the same level or at various levels) may be controlled not only by means such as the deflector 37 and the damper 38, but also by a suitable regulation of a supply of air admitted through the nozzle 24, or its equivalent.

Except in the case of comparatively high or large-capacity furnaces, I consider it advantageous to employ but a single flame jet, of the described character; and I prefer ordinarily to use air, rather than steam, as an auxiliary fluid; and, in order to facilitate the simultaneous insertion and/or dropping of a batch of units 14, or 14', into a furnace of the described character, I may render an apertured top closure plate or part 63, central of the plate 33, separately removable, securing the mentioned pins 42 thereto or therein in such manner that a considerable number of like or unlike units may be simultaneously lowered, together with the plate or part 63, into such a position as that illustrated in Fig. 1. If desired, the plate 63 may be of such restricted diameter that, upon the lateral withdrawal of supporting means such as a slideable bolt or bolts 64, (shown as manipulable by a cam ring 65 having a handle 66) this plate and the entire batch of units attached thereto may simultaneously drop into the quench tank, or its equivalent; and, in order that an entire batch or any number of units of the described character, or of any preferred character, may be conveniently withdrawn, I show the tank 18 as containing a wire basket or other foraminous receptacle 67. This basket, or its equivalent, is preferably of such diameter so as to fit somewhat loosely within the described tank; and it may be provided with any preferred elevating or withdrawing means, such as mere cords 68, or other flexible elements, the illustrated flexible members being shown as extending over pulleys 69 and as provided with handles 70.

Although I have herein described a single complete embodiment of my invention, it should be understood not only that various features of my invention might be independently employed but also that numerous modifications thereof might be devised, by those skilled in the art to which this case relates, without the slightest departure from the spirit and scope of my invention, as the same is indicated above and in the following claims.

For example, I may substitute for one or

more of the perforated cones 54 an imperforate cone or cones 67'. These latter are suitable not only for a more pronounced retardative effect but for an annealing effect similar to that produced by guards of the general type shown in Fig. 4,—as might be desired for the purpose of adapting a mast 14' to be subsequently tapped at 68'.

I claim as my invention:

1. In a heat treating and quenching organization: an upright furnace; and means for suspending treated units therein; a quench tank adapted to contain a liquid therebelow; means for releasing said units; and means mounted on said units separate from said suspending means for retarding the rate of descent of said units into said liquid.

2. A heat treating organization comprising: a quenching tank; a furnace; and means for supporting said furnace vertically above said quenching tank, said furnace comprising a central treating chamber surrounded by a substantially vertical inner wall and having a substantially uninterrupted passage therethrough in alignment with said quenching tank, top and bottom closure members removably mounted in the ends of said treating chamber, a vertical external enclosing wall surrounding said inner wall and forming a substantially uninterrupted annular heating passage between said walls, said external wall being provided with lateral inlet and outlet openings in opposite ends thereof, end closures for said heating passage, means for projecting a flame into said heating passage and a deflecting plate within said heating chamber for guiding said flame through said heating passage to produce a substantially uniform temperature within said treating chamber.

3. A heat treating organization comprising: a quenching tank; a furnace; and means for supporting said furnace vertically above said quenching tank, said furnace comprising a central treating chamber surrounded by a substantially vertical inner wall and having a substantially uninterrupted passage therethrough in alignment with said quenching tank, top and bottom closure members removably mounted in the ends of said treating chamber, means for suspending articles to be treated from said top closure, a vertical external enclosing wall surrounding said inner wall and forming a substantially uninterrupted annular heating passage between said walls, said external wall being provided with lateral inlet and outlet openings in opposite ends thereof, end closures for said heating passage, means for projecting a flame into said heating chamber and a deflecting plate within said heating chamber for guiding said flame through said heating passage to pro-

duce a substantially uniform temperature within said treating chamber.

4. A heat treating organization comprising: a quenching tank; a furnace; and means for supporting said furnace vertically above said quenching tank, said furnace comprising a central treating chamber surrounded by a substantially vertical inner wall and having a substantially uninterrupted passage therethrough in alignment with said quenching tank, top and bottom closure members removably mounted in the ends of said treating chamber, means for suspending articles to be treated from said top closure, means for releasing said suspended article, a vertical external enclosing wall surrounding said inner wall and forming a substantially uninterrupted annular heating passage between said walls, said external wall being provided with lateral inlet and outlet openings in opposite ends thereof, end closures for said heating passage, means for projecting a flame into said heating chamber and a deflecting plate within said heating chamber for guiding said flame through said heating passage to produce a substantially uniform temperature within said treating chamber.

5. A heat treating organization comprising: a quenching tank; a furnace; and means for supporting said furnace vertically above said quenching tank, said furnace comprising a central treating chamber surrounded by a substantially vertical inner wall and having a substantially uninterrupted passage therethrough in alignment with said quenching tank, a top cover plate, releasable means supporting said cover plate and adapted to permit the downward passage of said cover plate through said treating chamber, a bottom closure pivotally mounted in said treating chamber, a vertical external enclosing wall surrounding said inner wall and forming a substantially uninterrupted annular heating passage between said walls, said external wall being provided with lateral inlet and outlet openings in opposite ends thereof, end closures for said heating passage, means for projecting a flame into said heating chamber and a deflecting plate within said heating chamber for guiding said flame through said heating passage to produce a substantially uniform temperature within said treating chamber.

6. A heat treating organization comprising: a quenching tank; a furnace; and means

for supporting said furnace vertically above said quenching tank, said furnace comprising a central treating chamber surrounded by a substantially vertical inner wall and having a substantially uninterrupted passage therethrough in alignment with said quenching tank, a top cover plate provided with means for supporting treated articles, releasable means supporting said cover plate and adapted to permit the downward passage of said cover plate through said treating chamber, a bottom closure pivotally mounted in said treating chamber, a vertical external enclosing wall surrounding said inner wall and forming a substantially uninterrupted annular heating passage between said walls, said external wall being provided with lateral inlet and outlet openings in opposite ends thereof, end closures for said heating passage, means for projecting a flame into said heating chamber and a deflecting plate within said heating chamber for projecting and guiding said flame through said heating passage to produce a substantially uniform temperature within said treating chamber.

7. A heat treating organization comprising: a quenching tank; a furnace; and means for supporting said furnace vertically above said quenching tank, said furnace comprising a central treating chamber surrounded by a substantially vertical inner wall and having a substantially uninterrupted passage therethrough in alignment with said quenching tank, top and bottom closure members removably mounted in the ends of said treating chamber, a vertical external enclosing wall surrounding said inner wall and forming a substantially uninterrupted annular heating passage between said walls, said external wall being provided with lateral inlet and outlet openings in opposite ends thereof, end closures for said heating passage and means for projecting and guiding a flame through said heating passage to produce a substantially uniform temperature within said treating chamber, said last mentioned means including a projecting burner and a tangential deflecting plate mounted in said annular passage adjacent the inlet opening of said external wall.

In testimony whereof, I have hereunto set my hand at Los Angeles, California, this 17th day of November, 1926.

GEORGE E. BARNHART.
